UNITED STATES PATENT OFFICE

ERNST WEISSHUHN, OF TROPPAU, CZECHOSLOVAKIA, ASSIGNOR TO F. L. SMIDTH & CO.,
OF NEW YORK, N. Y., A CORPORATION OF NEW JERSEY

BAG

Application filed June 12, 1929, Serial No. 370,286, and in Germany July 7, 1928.

The invention relates to the manufacture of bags, of paper or other suitable material, either single ply or multiple ply, such as those which are made from previously formed tubes of material and are designed particularly for the reception of pulverulent material, such as hydraulic cement. It is concerned particularly with bags of the type commonly known as satchel-bottom bags in which each end of the bag, for convenience referred to herein as the bottom, is formed by folding both side members outwardly from a common line, then folding the end members inwardly against the side members, and finally folding the two side members inwardly one upon the other and upon the end members, the contacting surfaces being secured together by an adhesive. Bags of this type have long been known and it has also been known, in the case of multiple ply bags, designed to receive pulverulent material, that it has been difficult, without the exercise of extraordinary care in applying the adhesive, to make such bags entirely dust proof at the points where the lines of fold of the side members inwardly, one upon the other, meet the lines of fold of the end members. It is the primary object of the present invention to strengthen such bags and to render them more certainly dust proof without requiring special care in the application of the adhesive. A further object has been to effect an economy in the amount of material used in the formation of such bags.

In the accompanying drawings in which the invention is illustrated—

Figure 1 is a view in elevation of a unit length of a tube of material adapted for the formation of a bag, the lines of folding for the formation of an ordinary satchel-bottom bag being indicated by broken lines.

Figure 2 is a similar view of the ordinary satchel-bottom bag in which the preliminary folding of the bag at one end is illustrated and in which the other end is shown as completely formed and turned up against the side of the bag.

Figure 3 is a view similar to Figure 2, but showing a bag having the lower end completely formed in accordance with the pres-

ent invention and the upper end as partially formed, also in accordance with the invention.

Figure 4 is a view similar to Figure 1, but illustrating not only the lines of folding of each end or bottom of the bag in accordance with the invention, but the feature of economy of material, the lines of folding being indicated by broken lines and the economy feature by shaded portions.

Figure 5 is a detail view on a larger scale of one end or bottom of a bag partly folded in accordance with the invention.

Figure 6 is a detail view on a still larger scale of one end or bottom of a bag completed in accordance with the invention.

Figures 7, 8 and 9 are detail views in perspective and on a larger scale illustrating more clearly the successive operations of folding in forming one end of the top or bottom of a bag in accordance with the invention.

In order that the invention may be more readily understood, it will be desirable to describe first and briefly, by reference to Figures 1 and 2, the formation of the well known satchel-bottom bag from a tube of paper or other material formed in any suitable manner. Assuming that the unit tube is flattened, with opposite sides in contact, the side members a^1, a^2 of each end or bottom are folded outwardly from each other upon a common line, indicated at b^1, b^2 , the end members a^3, a^4 being at the same time folded inwardly upon the lines b^1, b^3 and b^2, b^4 .

The side members, a^1, a^2 with the end members a^3, a^4 , are then folded inwardly, one upon the other, on the lines b^5, b^6 . In Figure 2 the side member a^1 nearer the eye of the observer is shown as folded down flat against the body of the bag and the other side member a^2 is shown as folded down upon the first side member.

After this the first side member a^1 is folded over upon the second side member a^2 . The contacting surfaces, except as herein explained, are coated with an adhesive, so that they shall adhere closely together in the completed bag.

Bags of this type are commonly formed as valve bags in which the contacting surfaces at one end of the closure, 100

between the inturned end member and the overlying inturned portions of the side members, are left without adhesive so that a filling tube can be inserted for the purpose of filling the bag with the pulverulent material, such non-adhering surfaces being held together by the pressure of the contents of the bag after it is completely filled. Such valve filling opening is provided at one end of the top only of the bag, the bottom being completely closed at both ends. A rectangular strip or stay, indicated by broken lines at c , in Figure 2, is commonly applied with adhesive upon the folded end of the bag when the folding has been completed for the purpose of more strongly securing together the parts of the satchel-bottom.

Unless great care, inconsistent with economy, in manufacture, is exercised in applying the adhesive and pressing the parts together, unsealed channels are left along the lines b^5 , b^6 and b^9 , b^{10} through which leakage of the pulverulent material takes place. It is the principal object of the present invention to so construct the bag as to prevent such leakage without requiring the exercise of special care in sealing the bag.

In the production of the improved bag for the purpose of effecting an economy in the material used, the tube a , from which successive unit lengths are cut to form successive bags, is cut obliquely, as indicated by the lines a^5 , a^6 in Figures 4, 5 and 6, the end of one bag being matched against the adjacent end of the next bag. In this manner, as indicated by the hatched portions a' of Figure 4, a saving of about 4% of the material used for each bag is effected while, as will appear more clearly hereinafter, the strength and security of the bag are in nowise decreased. The folding of the ends of the bag in accordance with the invention is effected in the same manner whether the ends of each bag unit are cut off obliquely or not. It will also be understood that a valved filling opening d , such as that already described with reference to the old type of satchel-bottom bag, is provided at one end (the left-hand end in Figure 6) of the top of the bag by folding in the manner already described and omitting the adhesive, the formation of the bag in accordance with the invention being applied only at the other end of the top of the bag and at the two ends of the lower end of the bag.

In the formation of the improved bag the two side members a^1 , a^2 of the end or bottom of the bag are first folded outwardly from a common line b^1 , b^2 , as already described with reference to Figures 1 and 2. The two end members a^3 , a^4 are folded inwardly on the lines b^1 , b^3 and b^2 , b^4 (Figure 5). One side member a^2 is folded inwardly on the line b^5 , b^6 , but in accordance with the present invention the portion of the end member a^4 adjacent or corresponding to the

side member a^2 , instead of being folded over upon itself with the side member a^2 on the line b^5 , b^6 , parallel with the line b^1 , b^2 , is folded over on itself in one direction on the line b^6 , b^7 (Figure 7), from a median point b^9 in the line b^4 , b^6 , the line b^6 , b^7 being inclined outwardly toward the outer edge of the side member, and is folded over in the other direction from the same median point b^9 against the side member a^2 , on the line b^6 , b^8 , inclined inwardly toward the median line b^1 , b^2 . Then the second side member a^1 is folded inwardly on the line b^8 , b^9 (Figure 6) and the corresponding portion of the end member is at the same time folded in one direction from a median point b^9 in the line b^2 , b^4 , on the line b^9 , b^{10} (Figure 7), which is inclined inwardly toward the median line b^1 , b^2 , and is folded in the other direction from the same median point b^9 , upon itself, on the line b^9 , b^{10} , which is inclined outwardly toward the outer edge of the side member a^1 . The last mentioned portion of the end member is thus folded over against both side members. The folding of the end member in the manner described causes the side member a^1 to overlap the end member and the other side member to an extent greater than would be the case if the end member were folded only on the lines b^5 , b^6 , as will be seen by comparison of the lower end of the bag shown in Figure 3 with the lower end of the bag of ordinary construction shown in Figure 2. This folding stiffens the corner of the bag, preventing it from being forced outward by the contents and more effectually prevents escape of the material by affording greater areas of contact surfaces.

All of the contacting surfaces are coated with adhesive and thereby secured together and a rectangular strip or stay, indicated by broken lines c in Figure 6, is applied as already described with reference to Figure 2. Finally, all members may be further secured together by wire staples, as indicated at e in Figure 6, it being understood that where a valve opening is to be provided, as indicated at the left hand in Figures 5 and 6, the end member is not folded upon itself as above described but is folded as previously described with reference to Figure 1.

I claim as my invention:

1. A satchel-bottom bag formed from a tube of material and having the side members of the bottom folded outwardly from a common line, as at b^1 , b^2 , and each side member folded inwardly, as on the lines b^5 , b^6 , the end member a^4 being folded toward the side member, as on the lines b^2 , b^4 , and the portion of the end member adjacent to each side member being folded in opposite directions from a median point, as b^9 , b^8 , in the lines b^2 , b^4 , on lines b^6 , b^7 and b^9 , b^{10} inclined outwardly toward the outer edge of the respective side members and, from the same

median points, on the lines b^6 , b^8 and b^9 , b^{10} inclined toward the common line, the contacting portions being secured together.

2. A satchel-bottom bag formed from a tube of material cut at its ends at oblique angles in opposite directions and having the side members folded outwardly from a common line, as at b^1 , b^2 , and each side member folded inwardly, as on the lines b^3 , b^6 , the end member a^4 being folded toward the side members, as on the lines b^2 , b^4 and the portion of the end member adjacent to each side member being folded in opposite directions from a median point b^6 , b^9 , in the lines b^2 , b^4 , on lines b^6 , b^7 and b^9 , b^{10} inclined outwardly toward the outer edge of the respective side members and, from the same median points, on the lines b^6 , b^8 and b^9 , b^{10} inclined toward the common line, the contacting portions being secured together.

In testimony whereof I have affixed my signature.

ERNST WEISSHUHN.
